(57) **CLAIM**

The ornamental design for a record collection holder, as shown and described.

DESCRIPTION

FIG. 1 is a perspective view of the record collection holder showing a new design;

FIG. 2 is a front view of the holder of FIG. 1;

FIG. 3 is a rear view of the holder of FIG. 1;

FIG. 4 is a left side view of the holder of FIG. 1;

FIG. 5 is a right side view of the holder of FIG. 1;

FIG. 6 is a top view of the holder of FIG. 1; and,

FIG. 7 is a bottom view of the holder of FIG. 1.

The broken lines shown in FIGS. 2-5 and 7 are for the purpose of illustrating environmental structure and form no part of the claimed design.
